BUTTON

John W. Abell, Torrington, Conn., assignor to
 Turner & Seymour Manufacturing Company,
 Torrington, Conn., a corporation of Connecticut

Application January 5, 1935, Serial No. 468

4 Claims. (Cl. 24—101)

The present invention relates to improvements in buttons particularly of the type adapted for use in tufting mattresses, cushions and upholstery.

5 In one method of tufting, the tufting needle instead of being passed completely through the mattress or cushion is arranged to carry a loop through the mattress to which loop a button is secured, and then, after the needle is withdrawn, 10 the loop is drawn taut and is fastened to a button on the other side of the mattress. When using buttons with closed eyes it is necessary to "choke" the loop on the button. In other words, the loop is drawn through the eye of the button 15 and then is slipped over the head of the button thereby making it fast. Another method of making the button fast to the loop is to provide a button with an open eye which is merely hooked upon the loop. This saves the time of threading 20 the loop through the eye and then threading the head of the button through the loop.

An object of my invention is to provide a button with an open eye whereby it may be applied in the manner last described and a specific object of my invention is to provide means on such 25 a button which will facilitate the hooking operation.

Another object of my invention is to provide a button in which the open eye is so formed as to 30 prevent the button from being accidentally unhooked, at the same time permitting unhooking of the button intentionally whenever desired.

Other objects and advantages of my invention 35 will appear in the following description of a preferred embodiment and thereafter the novelty and scope of the invention will be pointed out in the claims.

In the accompanying drawing;

Figure 1 is a side elevation of my improved button with the eye of the button disposed edge-wise to view; and,

Fig. 2 is a similar view with the button turned through an angle of 90 degrees on its vertical axis.

As shown in the drawing, the button is provided with a head 10 and a wire shank 11. This shank is preferably fixed to the head and has a straight portion 12 projecting centrally from the head. Below the straight portion there is an offset 13 forming a recess and below this offset the wire is bent to form an eye 14 which lies in the plane of the straight portion 12 and hence is centrally disposed with respect to the head. The free

end 15 of the eye portion extends into the recess formed by the band 13 but is spaced from the walls of the recess.

In use the button may be attached to a loop or thread by pressing the straight portion 12 5 against the thread and drawing the button upwardly so that the thread will slide along the shank of the button following the offset past the free end 15 of the eye and thus entering the eye itself.

10 It will be observed that in this way the thread is readily guided into the eye, and once it has entered the eye it will be difficult for it to escape therefrom accidentally because the end 15 of the eye acts as a bar to the escape of the thread. 15 Only by turning the button and at the same time pressing it inwardly will it be possible to force the button off the thread.

Having thus described my invention what I claim as new and desire to secure by Letters 20 Patent of the United States is as follows:

1. A button comprising a head, and a wire shank extending from the head and formed into an open eye, the shank being laterally offset to 25 form a recess above the eye and the free end of the wire forming the eye projecting into said recess but spaced from the walls of the recess.

2. A button comprising a head, and a wire shank extending from the head and formed into an open eye, the shank being laterally offset to 30 form a recess above the eye and the free end of the wire forming the eye projecting into said recess but spaced from the walls of the recess, said shank being fixed to the head.

3. A button comprising a head, and a wire 35 shank extending from the head and formed into an open eye, the shank being laterally offset to form a recess above the eye and the free end of the wire forming the eye projecting into said recess but spaced from the walls of the recess, said eye being disposed in a single plane substantially 40 normal to the plane of the head.

4. A button comprising a head, and a wire shank extending from the head and formed into an open eye, the shank having a straight portion 45 and a portion forming a lateral recess above the eye, the free end of the wire forming the eye projecting into said recess but spaced from the walls of the recess, said straight portion and said eye being disposed in a common plane substantially 50 normal to the plane of the head.

JOHN W. ABELL.
